E. DIETZE

BOX STRAP FASTENER

Filed April 25, 1924

INVENTOR
Emil Dietze,
BY Fred W. Casken,
ATTORNEY

UNITED STATES PATENT OFFICE.

EMIL DIETZE, OF RICHMOND HILL, NEW YORK, ASSIGNOR TO AMERICAN CASTING AND MANUFACTURING CORPORATION, OF BROOKLYN, NEW YORK, A CORPORATION OF NEW YORK.

BOX-STRAP FASTENER.

Application filed April 25, 1924. Serial No. 708,951.

To all whom it may concern:

Be it known that I, EMIL DIETZE, a citizen of the United States, and resident of Richmond Hill, borough of Queens, in the 5 county of Queens, city and State of New York, have invented certain new and useful Improvements in Box-Strap Fasteners, of which the following is a specification, reference being had therein to the accompanying drawing.

My invention refers to box strap fastening devices. The strap with which it is used is of metal or other material and is of the kind that is ordinarily used for fastening 15 a band around a box, bale, or other package, in cases where it is essential that the ends of the strap should be closely united, so that they cannot be pulled apart or disjoined, and hence so that there cannot be any 20 unauthorized opening or pilfering of the package. A primary object of the invention, among many which might be mentioned, is to provide a fastening device which is the equivalent of a seal to be tightly attached to 25 the strap sections, so that it cannot be detached therefrom without breaking, and if detached cannot possibly be reattached, and if broken will immediately indicate that the box or package has been irregularly entered. 30 The invention, therefore, consists essentially in the sealing or locking fastener, having many peculiar and distinguishing characteristics, and in the construction and arrangement of the various parts substantially as 35 will be hereinafter described and claimed.

In the accompanying drawing illustrating my invention:

Figure 1 is a plan view of my improved seal or fastener, shown ready to be compressed upon two sections of a strap embraced thereby for the purpose of fastening the same together.

Figure 2 is a similar plan view of my improved device after the fastening device has 45 been duly compressed by suitable means and shows the side flanges forced down tightly upon the strap.

Figure 3 is an enlarged cross section of the parts shown in Figure 1 on the line 3, 3, 50 of Figure 1.

Figure 4 is a cross section on the line 4, 4, of Figure 2, and shows the relation of the various parts after compression.

Figure 5 is a side elevation of my improved device as indicated in Figure 2.

Figure 6 is a detail longitudinal section on the line 6, 6, of Figure 2.

Figure 7 is a transverse section, similar to Figure 3, of a modified form of the invention.

Figure 8 is a cross section on the line 8, 8, of Figure 9.

Figure 9 is a plan view of the form of the device delineated in Figure 8.

Figure 10 is a cross section on the line 10, 10 of Figure 12 of another alternative 65 form of the invention.

Figure 11 is a similar cross section of this form of the invention but shows the parts compressed together instead of being 70 open as in Figure 10.

Figure 12 is a plan view of the form of the device shown in Figure 10, with the strap section indicated in dotted lines.

Like characters of reference designate corresponding parts throughout all the figures of the drawing.

A and B designate two portions, sections, or ends of a strap intended to pass around a box or other package for the purpose of 80 strongly securing the same, and said ends overlap each other and are to be closely bound together, by means of a special seal or fastening device, in order that they cannot be pulled apart or tampered with.

The seal or fastener is made of metal or any other similar or effective material, preferably of square or rectangular form, though it may be made of any shape and be of any size and outline. I have shown several 90 different forms, which are the equivalents of each other, as they all do the same work and vary only in details.

In the form shown in Figures 1 to 6 the base of seal is a flat and unobstructed plate 95 1 having its opposite ends provided with raised parallel edges 2, 2, bent at right angles to the base 1, further the base 1 as well as the raised edges 2 are provided with a pair of slots 5, 5, located opposite to each other and cut out of the material of the seal, a portion of the cut in each case being as 100 stated in the base 1 and a portion in the edge 2, and there being a part of the cut out material, as 3, left integral with the seal and projecting horizontally from the raised

105

members 2 so as to lie over a portion of the slot 5, as clearly indicated in Figures 1 and 3. Ordinarily this integral lip or projection 3 does not comprise all the material 5 taken out by cutting the slot 5, but only a portion of it, the rest being discarded, as it is only desired to strike out short lips 3 which when the sides 2 are bent down upon the strap ends lying between these sides, as 10 shown may intervene between the sides 2 and the strap ends and have the function of compressing said straps or a portion thereof into the slots 5 and thereby form an effectual plant or binder, so that the parts will all be bound very closely and intimately together, and so that it will be impossible to dislodge the seal or fastener from the strap sections, for the only way that the strap can be removed from the box or bale 20 will be by cutting or breaking it. In Figure 1 these parts are all shown in the relative position which they take when the uncom- 25 pressed fastener is applied to a pair of strappings. After some suitable press has been applied to the seal and the edges 2 have been pressed down on the strap ends, the parts will occupy the position shown in Figures 2 and 4 and in the side view of Figure 5, as also the section of Figure 6, where 30 it will be seen that the lips 3 have been bent under the sides 2, and the latter have been pressed down so as to be parallel with the base 1 instead of being at right angles to said base. The lips 3, as it were, when so 35 bent add a segment of thickness to the sides 2, the effect of which is to press down cer- 40 tain portions of the edges of the straps A and B into the slots 5, as seen in Figure 4, at the edges 11, which latter show a some- 45 what curved form, as in Figures 2 and 5. The seating of portions of the straps A and B in slots 5 makes a very effectual inter- locking.

In the form of the invention illustrated in 45 Figures 7, 8 and 9 the same general outline and list of parts obtains as in Figures 1 to 6, with the exception that the lips or pro- 50 jections 4, 4, instead of coming out horizontally, as 3, 3, from the raised sides 2, rise ver- 55 tically from the base 1^a and hence lie par- 60 allel to the vertical sides 2^a, there being slots 6, 6, similar to the aforesaid slots 5. In this 65 form the strap sections A and B when the seal is placed thereon, will lie on top of the 70 lips 4, instead of being underneath the lips 3, in the first form, and hence when the sides 2^a are compressed upon the strap sec- 75 tions, as shown in Figure 9, the upper ends 80 of the lips 4, will serve to cause the portions 85 of the strap sections to be lifted or curved upwardly by the force of the clamp- 90 ing effect into the slots 6, 6, as shown in the 95 section of Figure 8 and in the plan of Figure 9; but the locking engagement of all 100 the various parts is substantially the same,

and a securely combined fastener results in the same manner as in the first form of the invention, the changes and differences alluded to being only trifling and without any real change of result, the chief point in this 105 form as in the other is to furnish means by which when the side flanges are compressed, the material along the edges of the strap sections will be forced into the slots in the fastener. 110

In Figures 10, 11 and 12 I show a further alternative form, with equivalent means for producing the same result, and varying only in minor features which are related to each other in a somewhat different way. In this 115 form 7 denotes the base of the seal having the sides 8 which are bent up from the edges of the base 7 and are provided with opposite slots 10 which have been cut into the sides 8 as well as into the bottom 7. These 120 sides 8 are preferably inclined instead of being bent at right angles, and when so inclined they will be closer together at the top than at the bottom and hence the straps A and B will be kept in place and if they 125 rise a little will not become disengaged from the fastener, the inclinations of the sides in this case having the same effect as the horizontal projection of the lips 3. The portion 9 cut out of each of the slots 10 and 130 left integral with the base 7 is bent over upon same in the original formation of the seal, thus thickening the base 7 at the ends of the slots 10 and providing the same kind of a thickened abutment on the base as is 135 provided by the horizontal lips 3 after the raised sides 2 have been bent down thereon; for it will be seen that with these thick portions 9 upholding the strap ends A and B, when the sides 8 are pressed down upon the 140 said strap ends, the result will be exactly as indicated in Figure 11 where the edges 145 of the strap sections will be lifted upwardly by the members 9 and flexed over said members and into the slots 10 thereby 150 causing the same kind of a rigid embedding of the material of the strap in the slots of the fastener, as is accomplished in the other forms of the invention, with the same firm 155 and unyielding union. 160

Many changes in the exact form, shape and relative location of various members, parts, and connections may be made without exceeding the scope of my invention.

Having thus described my invention, what I claim as new and desire to secure by Letters Patent is:

1. In a box strap fastener, a seal plate 165 having parallel raised edges and opposite slots cut partly in the edges and partly in the plate to leave a portion of the cut out material to form inner integral projections, in combination with overlapping strap sections against which the raised edges are bent 170 to compress the said raised edges, the pro- 175

jections and the strap ends together, and force the latter into the slots.

2. In a box strap fastener, a seal plate having parallel raised edges and opposite slots cut partly in the edges and partly in the plate to leave a portion of the cut out material to form integral projections extending inwardly from the slots, in combination with a strap whose ends overlap between the raised edges and against which the edges are adapted to be bent to force the projections against the strap and press the strap into the slots.
3. In a box strap fastener, a seal plate having parallel raised edges and opposite slots cut partly in the edges and partly in the plate to leave a portion of the cut out material to form inner integral projections adapted to lie under and thicken said edges when they are bent down inwardly, in combination with overlapping strap ends which lie between the said edges, and against which the latter are compressed with the inner integral projections between them to drive the material of the strap into the slots with a curved embedded effect.

4. In a box strap fastener, a seal having a flat base provided with parallel right-angled raised edges and out of which slots

are cut partly in the base and partly in the edges to leave a portion of the cut out material to form inwardly extending horizontal projections that lie parallel to the flat base, in combination with overlapping strap members against which the raised edges are compressed with the horizontal projections between them and the base to force the material of the strap members with a curved embedded effect into the slots of the base.

5. In a box strap fastener, a seal device having a base member and parallel raised edges, said base and edges being formed with slots cut partly in the base and partly in the edges to leave a portion of the cut out material to form integral projections located between the raised edges and the base to furnish thickened points which serve to compress the material of the strap section into curved form at certain points on the edges, and cause said compressed material to enter the slots in the seal, whereby an interlocking inseparable combination of the seal and strap results.

In testimony whereof I hereunto affix my signature.

EMIL DIETZE.
